UNITED STATES PATENT OFFICE.

FERNLEY H. BANBURY, OF ANSONIA, CONNECTICUT, ASSIGNOR TO BIRMINGHAM IRON FOUNDRY, OF DERBY, CONNECTICUT, A CORPORATION.

MACHINE FOR TREATING RUBBER AND OTHER HEAVY PLASTIC MATERIAL.

1,235,757.

Specification of Letters Patent.

Patented Aug. 7, 1917.

Application filed April 20, 1917. Serial No. 163,420.

To all whom it may concern:

Be it known that I, FERNLEY H. BANBURY, a subject of the King of Great Britain, residing at Ansonia, in the county of New Haven and State of Connecticut, have invented a new and useful Improvement in Machines for Treating Rubber and other Heavy Plastic Material; and I do hereby declare the following, when taken in connection with the accompanying drawings and the characters of reference marked thereon, to be a full, clear, and exact description of the same, and which said drawings constitute part of this application, and 15 represent, in—

Figure 1 a view in end elevation of a machine for treating rubber and other heavy plastic material constructed in accordance with my invention.

20 Fig. 2 a broken transverse sectional view of the same.

Fig. 3 a broken view in longitudinal section through one of the chambers, illustrating a sliding door for closing the opening in the bottom thereof.

This invention relates to an improvement in machines for treating rubber and other heavy plastic material, and particularly to machines for this purpose in which the casing is of a duplex character, that is, having two communicating chambers in each of which a rotor is mounted, such, for instance, as shown in United States Patent No. 1,200,971, dated October 3, 1916.

35 To provide for the delivery of material from the cylinders after it has been sufficiently treated, a single door has been arranged to swing away from a centrally arranged opening in the center of the casing.

40 The object of this invention is to provide a slot in each section of the casing so that the material instead of being discharged in a large mass, will be delivered in rough slice-like pieces; and the invention consists in the 45 construction hereinafter described and particularly recited in the claims.

In carrying out my invention, I employ a casing 4 comprising two cylindrical chambers 5 and 6, as in the patent above-referred to, and mounted to rotate in the chambers are blades 7 and 8 as in the patent above mentioned. In each chamber I form one or 50 more slots 9 which are adapted to be closed by slides 10 which rest upon horizontally arranged supports 11 and 12, the slides be-

ing constructed and arranged to close the slots 9 in the chambers. These slides may be operated in any desired manner. Preferably and as herein shown, they will each be connected with a piston rod 13 connected to a piston-head 14 in the cylinder 15 to which cylinders steam, water or air may be admitted or discharged to move the piston heads back and forth as desired. By using slides, the operation of moving them is simplified, and by providing a slide in each section or chamber of the casing the material being treated will be discharged or pushed out by the rotation of the blades in slabs or slab-like pieces rather than in a lump, as will be the case with a single, centrally arranged opening, unless that centrally arranged opening be made so small as to be impracticable for general use because it would require so much time to discharge the load.

I claim:

1. In a machine of the class described for treating rubber and other heavy plastic material, the combination with a double cylindrical casing formed with a slot in each cylinder, of slides adapted to close said openings.

2. A machine for treating rubber and other heavy plastic material comprising two cylindrical chambers, each formed with a slot, and a slide adapted to close the said slots.

3. In a machine for treating rubber and other heavy plastic material, the combination with a casing having two chambers, each formed with a discharge slot, of slides adapted to close the said slots, and horizontally arranged supports on which said slides may be moved.

4. A machine for treating rubber and other heavy plastic material comprising a casing having two cylindrical chambers each formed with a slot, slides adapted to close said slots, and means including a piston, a cylinder for moving said slides back and forth.

In testimony whereof, I have signed this specification in the presence of two subscribing witnesses.

F. H. BANBURY.
